UNITED STATES PATENT OFFICE.

HERMAN A. PAQUETTE, OF FAIRMOUNT HEIGHTS, MARYLAND.

HINGE.

SPECIFICATION forming part of Letters Patent No. 793,023, dated June 20, 1905.

Application filed September 12, 1904. Serial No. 224,191.

To all whom it may concern:

Be it known that I, HERMAN A. PAQUETTE, a citizen of the United States, residing at Fairmount Heights, in the county of Prince George 5 and State of Maryland, have invented certain new and useful Improvements in Hinges, of which the following is a specification.

My invention relates to improvements in hinges.

10 The object of my invention is to provide a hinge which combines simplicity of manufacture and assembling and which when once placed upon a door or blind cannot be removed by any one when in its locked position—that 15 is, when the leaves are parallel with each other.

This invention relates, furthermore, to an improvement of this kind in which the upper and lower portions of the pintle are made integral with the rear of one of the hinge-sections, leaving the intermediate portion of the 20 pintle free for the purpose of allowing the slotted sleeve of the abutting hinge-section to snugly embrace and revolve around the pintle.

A further object of this invention is to provide a hinge of this kind in which the slotted sleeve of the abutting hinge-section has a greater bearing-surface upon the lower part of the hinge, thereby rendering it more substantial and wear-resisting.

30 With these and other objects obvious from the structure as represented my invention consists in the features, details of construction, separately and in combination, as will be described in connection with the accompanying drawings and then pointed out more particularly in the claims.

In the drawings, Figure 1 is a plan view of the hinge; Fig. 2, a perspective view; Fig. 3, a side elevation, partly in section; Fig. 4, a 40 transverse sectional view; Fig. 5, a perspective view of a detached part; Fig. 6, a vertical section of part of the pintle in the countersunk portion of the butt; Fig. 7, a plan view, partly in section, of the pintle and countersink; Fig. 8, a transverse sectional view on the line $x-x$ of Figs. 1, 2; and Fig. 9, a perspective view of the sleeve.

Referring to the drawings, 1 represents a hinge-section adapted to be mounted upon the 50 jamb of a door or upon the casing of a win-

dow and having both faces finished for outside use, so that when it is desired to use said hinge on right and left hand jambs this can be done without additional work and expense. Both faces of this hinge-section are provided 55 with beveled or countersunk orifices 2 for the reception of screws. A butt portion 3 is made integral with the rear portion of the hinge-section 1 and has welded to it or, if desired, cast in one piece a pintle 4, extending along 60 the entire rear of the hinge-section. At its extremity or upper portion the pintle 4 is fixed to the hinge-section body by means of a shoulder 5, this shoulder extending away from the body of the hinge and spacing the pintle 65 from the rear of the hinge and leaving an opening for insuring easy and unobstructed movement to the abutting hinge-section 6. This hinge-section or movable hinge portion is provided with countersunk orifices 7 on its 70 upper or outer side, the surface adjacent the door being left in its unfinished or unpolished state, since this section will always have its unfinished face against the door edge however applied and used. A knuckle or walls 8 are 75 formed upon the rear of said hinge-section 6, said knuckle having a cylindrical bore extending from end to end corresponding in diameter to the diameter of the pintle, over which it is adapted to slide. One side of the said knuckle 80 is provided with a slot 9, corresponding in shape to the shoulder 5 and arranged to be slid off and on the pintle and to be positively locked against removal by any divergence from the angle necessary to bring said slotted 85 sleeve or knuckle in register with the shoulder 5.

In order to give to the hinge-leaves when adjusted the finished appearance of the ordinary hinge, I provide a sleeve 10, having a 90 slot by means of which it may readily be slipped over the upper end of the pintle. The extreme end of the pintle is recessed and provided with screw-threads arranged to receive the cap 11. If desired, the butt portion 3 can be countersunk around the pintle 95 welded to it, in which case the abutting portion of the hinge would have its lower ends formed so as to snugly sit within said countersunk portion, as shown in Fig. 6.

In the course of the manufacture of this invention it is very desirable for the purpose of increasing the strength and durability of the pintle to have the intermediate portion of the pintle made separately, as indicated in Fig. 3 of the drawings, and then in the course of molding the portion into shape to insert this piece while the metal is still in its molten condition. In this manner the pintle is practically a single piece in its completed form.

In the hinge produced by my invention it is highly important that the pintle be of sectional formation—that is, an intermediate portion independent of the other portion—15 for the reason that by such a construction I am enabled to cast the pintle-leaf of the hinge with the upper and lower portions of the pintle integral therewith, while the central portion of the pintle—that is, the portion 20 embraced by the knuckle—may be made of other wear-resisting material, such as steel or wrought-iron. The hinge is thereby materially reduced in cost of manufacture, while at the same time the parts subjected to wear 25 are of extreme durability. It will be further noted that the shoulder 5, which joins the leaf and the pintle near the upper end of the latter, is gradually reduced in thickness from its junction with the leaf toward the pintle. 30 This feature is also of material importance, for the reason that it permits a reduction in the width of the slot 9 of the knuckle, thereby providing for a larger bearing-surface between the knuckle and the pintle than would 35 be possible were the shoulder 5 of the same thickness as the plate. Furthermore, the specific shape of the shoulder is practically triangular in horizontal section, with the apex joining the pintle, so that the slot 9 is of 40 course of inverse shape, so that the apex of the slot formation is adjacent the bore of the knuckle, thus permitting of the greatest possible circumferential bearing of the knuckle

upon the pintle without preventing the disengagement of the parts.

Having described and ascertained the nature of my invention, what I claim, and desire to secure by Letters Patent of the United States, is—

1. In a hinge the combination, with the 50 leaves, one of said leaves having permanently connected to its upper and lower portion a pintle, the upper portion of the hinge connecting the pintle formed with a grooved shoulder, the other of said leaves having a 55 longitudinally-slotted sleeve arranged to pass the grooved portion of the abutting hinge-section, as described.

2. In a hinge, a pintle-leaf having formed therewith the upper and lower sections of the 60 pintle, a grooved shoulder joining the upper end of the pintle with the leaf, an independent central pintle-section secured to the portions formed with the leaf and a leaf having a longitudinally-slotted knuckle arranged to 65 engage said central pintle-section.

3. In a hinge a pintle-leaf having formed therewith the upper and lower sections of the 70 pintle, a grooved shoulder joining the upper end of the pintle with the leaf, an independent central pintle-section secured to the portions formed with the leaf, a leaf having a longitudinally-slotted knuckle arranged to engage the said pintle-section, a loose sleeve having a slot formed to correspond with the 75 grooved shoulder and a cap having threaded engagement with the pintle and overlying said sleeve to prevent disengagement of the parts.

In testimony whereof I affix my signature in 80 presence of two witnesses.

HERMAN A. PAQUETTE.
